UNITED STATES PATENT OFFICE.

EDWIN T. GREENFIELD, OF MONTICELLO, NEW YORK.

JUNCTION-BOX.

No. 807,262.

Specification of Letters Patent.

Patented Dec. 12, 1905.

Application filed January 23, 1904. Serial No. 190,397.

To all whom it may concern:

Be it known that I, EDWIN T. GREENFIELD, a citizen of the United States, residing at Monticello, in the county of Sullivan and State 5 of New York, have made a new and useful Invention in Junction-Boxes, of which the following is a specification.

My invention is directed particularly to an improvement upon a junction-box for electrical conductors disclosed in a prior patent granted to me on the 30th day of January, 1900, by the United States Patent Office and bearing No. 642,521. The box disclosed in the before-mentioned patent is composed of a cast base 15 having semicircular openings for receiving the inner ends of conduits, and the lid or cover of said box is provided with similar semicircular openings, in the inner faces of which are cast integral with the box elliptical disks 20 adapted when the two parts of the box are put together to completely close all of the openings, the arrangement being such that these elliptical disks may be broken out by a tool, as desired, when the junction-box is put in 25 place. It is found in practice in the use of such boxes that oftentimes in breaking out the disks the inner walls of the cover or that portion with which the disks are integral are chipped out or broken away, thereby causing 30 said walls to have a thickness at the point or points where the conduit tube or tubes enter the same less than the thickness of the wall of the box proper, and often, in fact, breaking down the inner wall of the box so as to leave 35 an opening at that point, thus making the same worthless, so that it has to be thrown away.

The fire underwriters in many cities require that the walls of electrical junction-40 boxes shall be as nearly the same thickness as possible throughout and that the boxes when in use shall be without holes or openings; and it was with the object of overcoming the objectionable features of my before-mentioned 45 box that the present invention was devised, and the same will be fully understood by referring to the accompanying drawings, in which—

Figure 1 is a plan view of a two-part cast-50 metal box with a part of the lid or cover broken away. Fig. 2 is a sectional view of the same, taken on the line X X, Fig. 1, and as seen looking thereat from left to right in the direction of the arrows, my improvement 55 being shown in both views. Fig. 3 is a plan view of a ceiling switch-box as seen looking

into the interior thereof, the cover being removed, two of the disks being broken out and the other two being in normal position, and an opening provided in the center of the base of 60 the box for a gas-pipe or hanger. Fig. 4 is a sectional view taken through Fig. 3 on the line Y Y and as seen looking thereat from the top toward the bottom of the drawings in the direction of the arrows, the junction-boxes 65 illustrated in the drawings being of usual form, except that they embody my improvement, as will now be described.

Referring first to Figs. 1 and 2, B represents the base, and A the cover, of a two-part junction-box having on one side three hollow half-necks E E' E'' and on the opposite side a single hollow half-neck E⁵ for the admission of a gas-pipe, E³ E⁴ being similar hollow half-necks to E E' for the admission of armored 75 conduits. G and G are lugs on opposite sides of the base for centering the cover or lid in its correct position, and S S are screws for securing the bottom of the box to its proper support. The lid or cover is provided with 80 similar half-necks, as shown, and at the inner end of each of the several half-necks is cast integral with its corresponding part half-disks D, overlapping each other and located in a plane or planes parallel with the inner 85 face of the box and as shown in Fig. 2. The inner portion of the half-necks are undercut between them and the disks, as shown at K K, so as to make it possible on inserting a tool 90 in the corresponding neck to break away said half-disk without injuring or impairing in any way the inner wall of the box. When the two parts of the box are put together as ordinarily cast, therefore, there will be no access to the interior thereof. However, when 95 it becomes necessary to use it the semicylindrical disks are driven inward by a tool in the same manner that the elliptical disks are driven inward in the junction-box disclosed in my prior patent, it being apparent that by 100 reason of the undercut nature of the necks in Figs. 1 and 2 and the cone-shaped extensions thereof, as shown in Fig. 4, there can by no 105 possibility be effected a breaking away of the surface of the box which would make the walls thereof any thinner than before said disks were broken away.

In Figs. 3 and 4 is shown a ceiling junction-box provided with lugs or ears F F F F for securing it by screws S directly to the ceiling, M being a gas-pipe or hanger opening in the center of said box. In this form of the in- 110

vention complete circular disks D D are cast integral at the outer ends of cone-shaped necks N N on the outside of the box and in a plane or planes parallel with the base thereof, 5 as clearly shown, and when said disks are broken away by a tool inserted within the box the necks will have the smooth inner surfaces and even edges, as illustrated in Fig. 4, without diminishing the thickness of the walls of 10 the box or in any way injuring or impairing the same.

Having thus described my invention, what I claim, and desire to secure by Letters Patent of the United States, is—

15 1. A junction-box having a series of inleading necks and a series of closing-disks therefor cast integral with the walls of the box and in planes parallel therewith, the thickness of said disks being less in each instance than 20 that of the corresponding wall of the box.

2. A junction-box having one or more hollow inleading necks cast integral therewith and closing-disks therefor cast integral with the necks, the construction being such that

25 said disks may be broken down or removed without injuring or impairing the structure.

3. A junction-box having an inleading neck and a disk at one end thereof cast integral with the box, said disk being in a plane parallel with the wall of the box and so constructed 30 that it may be broken away without injuring or impairing the structure.

4. A junction-box having an inleading neck and a closing-disk therefor both cast integral with the box, said disk being located in a plane 35 parallel with the inner wall of the box and the inner end of the neck undercut between it and the disk, whereby the latter may be removed on inserting a tool without injuring or impairing the wall of the box. 40

In testimony whereof I have signed my name to this specification in the presence of two subscribing witnesses.

EDWIN T. GREENFIELD
